VENDING APPARATUS

Benjamin W. Fry, University City, Mo.

Application January 3, 1939, Serial No. 248,983

7 Claims. (Cl. 312—94)

This invention relates to vending machines, and with regard to certain more specific features, to coin-actuated vending machines.

Among the several objects of the invention may be noted the provision of a vending machine of the class described which is particularly adapted for the dispensing of units of relatively large size and individually of relatively substantial rigidity, such as boxes of soap chips or flakes, boxes of cereals, and the like; the provision of a vending machine of the class described embodying improved escapement means for bringing successive units into position to be dispensed, and to dispense said units quickly and positively, one at a time, without any possibility of delivering more than one unit for one coin deposit; the provision of a vending machine of the class described embodying individual unit-supporting trays which, after the units thereon are dispensed, collect unobtrusively at a position and in a manner so as not to occupy more than a minimum of space, and so as not to interfere with or impede the dispensing of further units; the provision, in a vending machine of the class described, of means preventing the receipt by the machine of a coin in the event that all of the units in the machine have been dispensed; and the provision of a vending machine of the class described which is simple and economical in construction and operation. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a front elevation of a vending machine embodying the present invention;

Fig. 2 is an enlarged elevation of the machine of Fig. 1, with a front panel removed;

Fig. 3 is a vertical cross section taken substantially along line 3—3 of Fig. 2;

Fig. 4 is a fragmentary vertical cross section taken substantially along line 4—4 of Fig. 2;

Figures 5 and 6 are views similar to a part of Fig. 4, illustrating certain alternative operating positions; and,

Fig. 7 is a horizontal cross section taken substantially along line 7—7 of Fig. 2.

Similar reference characters indicate corresponding parts throughout the several views of the drawings.

Referring now more particularly to Figures 1, 2 and 3, it will be seen that the vending machine embodying the present invention is mounted within a relatively tall rectangular sheet metal

casing indicated generally by numeral 1. The casing 1 includes a removable front panel 3, which is secured or locked to the casing as a whole by suitable locking mechanism 5 near its top edge. 5 At its bottom, the front panel 3 has a rectangular opening 7, through which moves a pivoted delivery device 9, hereinafter to be more specifically described. Along its right-hand edge, the front panel 3 carries a coin-receiving escutcheon plate 11, a bad coin or slug delivery chute 13, and a suitable slot through which passes the manipulative end of a handle or operating lever 15.

Numeral 17 indicates an inner container of general box-like structure. The container 17 comprises rectangular sheet metal side walls 19, which are outwardly flanged, as indicated at numerals 21, at their front edges, and inwardly flanged, as indicated at numeral 23, at their rear edges. To properly space apart the side walls 19, a sheet metal strip 25 is affixed across the upper front edge of the box-like structure 17, to the two front flanges 21; another sheet metal strip 27 likewise extends across the front at about the level of the slug chute 13, and is likewise secured to the two front flanges 21. A portion of the strip 27, indicated by numeral 29, is bent inwardly into the box 17 so that it slopes downwardly, as indicated in Figure 3, for purposes hereinafter to be described. Numeral 31 indicates a rectangular plate which is provided with an in-turned upper reinforcing edge 33, and perpendicular extensions or ears 35 at its ends, the ears 35 respectively being affixed to the upper rear corners of the side plates 19, thereby further to aid in spacing said plates apart. The plate 31 is parallel to the back flanges 23, but is spaced a sufficient distance therefrom that, as the box-like structure 17 is inserted into the outer casing 1, it is suitably positioned with the front face of the box-like structure 17 flush with the front face of the casing 1. A fourth spacing member for the side walls 19 comprises a channel piece 37 that is secured, inside the box-like structure 17, to the back flanges 23, at the bottoms of said back flanges.

The box-like structure 17 is correctly positioned laterally in the outer casing 1 by means of angle pieces 39 and 41, which are affixed to the respective side walls of the casing 1 near the top thereof, and by angular spacing pieces 43 and 45 which are secured to the side walls 19 at the bottoms thereof. The left-hand space 47 thus provided, considered from the viewpoint represented by Fig. 2, is considerably narrower than the corresponding right-hand space 49. Into the latter space 49 fits a major portion of the operating mechanism of the machine.

The inner edges of the relatively long upper portions of flanges 23, indicated by numerals 51, 60 constitute tracks for guiding the movement of

certain tray pieces indicated by numerals 53. Each tray 53 (see also Fig. 7) comprises a flat rectangular metal plate provided, along its lateral edges near the rear corners thereof, with notches 55 adapted to receive and slide upon the track 51, and with a centrally located rectangular hole 57 parallel to and near the rear edge of said plate 53, and preferably substantially in line with the notches 55. The length from front to back of each of the plates or trays 53 is sufficient that, with a tray in horizontal position and its notches 55 on the tracks 51, the front edge of said tray rests lightly upon the sloping portion 29 of cross piece 27 (see Fig. 4).

Numerals 59 indicates a sheet metal hook or like member mounted on the rear wall of exterior casing 1, so that its front or hooking end 61 projects substantially in the plane of flanges 23. At the level of the end 61 of the hook 59, the two flanges 23 are sharply reduced in width, as indicated at numerals 63, so that the separation between their respective edges increases (see Fig. 2). These edges, below these points 63, are spaced apart a sufficient distance so that the notches 55 of trays 53 no longer will engage said edges, but, on the contrary, the end 61 of hook 59 will enter the openings 57 in the trays so that they pivot and hook upon and stack with other trays so discharged in vertical positions on the hook 59, all as shown in Figures 2 and 3. The tracks heretofore indicated by numeral 51 may be considered to terminate, downwardly, at the points 63 where this increased separation between the edges of flanges 23 is brought about.

Somewhat below the level of the points 63, the facing inner surfaces of the side walls 19 are provided with angle-pieces 65, the projecting surfaces of which slope downwardly toward the front of the machine. Preferably the projecting surfaces are extended rearwardly in a horizontal plane for a short distance, to abut the rear flanges 23, as indicated by numeral 67 in Fig. 3. The angle pieces 65 and their said extensions 67 constitute guiding means for delivering packages to be dispensed into the pivoted dispensing device 9. Further to assist in such guiding, and to assure the proper lateral positioning of said packages, two tabs or ears 69 are struck inwardly from the side walls 19, as indicated in Figures 2 and 3.

The pivoted delivery device 9 comprises a box-like sheet metal member with an open top 71. It is pivoted to the side walls 19 by screws or like members 73 mounted near its lower front corners. The back wall of the box has an extension, indicated by numeral 75, which is bent sharply downwardly and rearwardly, and has a further bent end 77 which, when the box 9 is tilted forwardly to the dotted line position shown in Fig. 3, abuts the under side of the projecting surface of angle pieces 65, to limit the forward rotating movement of said box 9. Preferably the front wall of the box 9 is provided with a thumb notch 79, to facilitate manipulation of the box 9.

Numerals 81 indicates a rectangular plate somewhat similar to the plate 31, which is likewise provided with an in-turned upper reinforcing edge 83 and perpendicular extensions or ears 85 at its ends, the ears 85 respectively being affixed to the outer surfaces of the back edge of the side walls 19 at a location just above the points 63. The plate 81 is parallel to, but spaced from, the rear flanges 23. It serves a reinforcing and spacing function similar to that of the plate 75

31, but in addition constitutes mounting means for an escapement device now to be described.

Numerals 87 (see also Fig. 4) indicates a channel-shaped piece, the upper flange 89 of which 5 is at an obtuse angle to the rear web thereof, and the lower flange 91 whereof is at right angles to said rear web. The channel piece 87 is just sufficiently long to fit between the ears 85. At its ends, the channel piece 87 carries perpendicular ears or extensions 93, which are pivoted, 10 as by screws 95, near the lower edges of the ears 85. At its right-hand end, an angle bracket 97 is secured to the under face of the lower flange 91 of the channel piece 87, and to the depending face of this bracket 97 is pivoted, as by a screw 99, a connecting bar 101.

Numerals 103 indicates a relatively rigid sheet metal strip that extends across between the ears 85. At its ends, angle brackets 105 are mounted 20 on the strip 103, and the angle brackets 105 are pivoted, as by screws 107, to the ears 85, so that the strip 103 as a whole may pivot on the screws 107. A suitable coil spring is provided on one or each of the screws 107 to urge the strip 103 25 to rotate in a clockwise manner, when considered from the viewpoint represented by Fig. 4. The lower or front edge of the strip 103 is therefore normally resiliently engaged against the back surfaces of back flanges 23.

Numerals 109 (Fig. 4) indicates a generally rectangular plate that is mounted on the outside surface of the right-hand side wall 19, in the space 49, as by bolts and nuts 111. The plate 109, however, is spaced from the side wall 19, as by suitable spacer strips indicated by numeral 113. Extending upwardly from the outer surface of plate 109 is a generally rectangular projecting area 115, the height of which above the surface of the plate 109 is preferably just slightly greater than the thickness of a coin, such as a dime, for which the machine is designed to operate. The upper edge 117 of the projecting area 115 constitutes a coin guiding means in a manner hereinafter to be described.

Pivoted in the region of its point on the projecting area 115 by means of a screw 119 is a quadrant-shaped operating lever or plate 121, from the forward edge of which extends the manipulating handle 15 hereinbefore referred to. Extending radially outwardly from the rearward edge of the quadrant plate 121 is an extension 123, the peripheral edge of which is provided with ratchet teeth 125. Numeral 127 indicates a pawl, pivoted on a screw 129, and resiliently maintained in position by a tension spring 131. The dog 127 engages the teeth 125 on projection 123 in both directions of rotation of the quadrant plate 121, to prevent any reversal of rotative direction of movement thereof during the period during which said pawl 127 is in engagement with the ratchet 123.

The curved upper edge of the quadrant plate 121 comprises a series of angular sections 133, 135 and 137 of progressively greater radius. A shoulder 139 is provided between sections 133 and 135, and a shoulder 141 between sections 135 and 137.

Numerals 143 indicates a circular slot in the quadrant plate 121, the ends of which cooperate 70 with a screw 145 mounted in the projecting area 115, to limit the rotative movement of the quadrant lever 121 in both directions. The free end of connecting bar 101 is pivotally connected to the quadrant plate 121 by a screw 146.

Numeral 147 indicates a lever that is pivoted

as on a screw 149, between the side wall 19 and the rectangular plate 109. At its forward, lower edge the lever 147 has a projection 151, which extends through an opening 153 in the plate 109 and rides upon the circular edge of quadrant plate 121. A tension spring 155 urges the lever 147 at all times to rotate downwardly, thereby pressing the projection 151 firmly against the edge of quadrant plate 121.

Near its upper edge, the plate 109 is provided with a coin-guiding chute 157, which has a hopper-like upper end, and a lower delivery end positioned just above the rearward edge of projecting area 115 on plate 109.

Numeral 159 indicates a pin, such as a screw, which is mounted on the quadrant plate 121 near the upper edge thereof, at about the central portion of angular section 137. The head of pin 159 extends substantially entirely across the space between the surface of plate 109 and the quadrant plate 121, for reasons hereinafter to be made clear.

A tension spring 161 is hooked to the rear edge of the quadrant plate 121 in such manner as to urge it to rotate in clockwise direction, when considered from the viewpoint of Fig. 4, at all times. This means that the quadrant plate 121 will normally maintain the position illustrated in Fig. 4, unless manually actuated to do otherwise.

Numeral 163 indicates generally a coin selecting device, the details of which need not be gone into herein. It suffices to say that the selecting device 163 takes coins delivered to the opening 11 and sorts good coins from bad coins, delivering the good coins to the hopper-end of chute 157 and the bad coins, or slugs, to the reject chute 13. Coin selecting devices of various sorts may be used in connection with the vending apparatus of the present invention.

Numeral 165 indicates a shelf or bracket that extends outwardly from the right-hand side wall 19, and receives and supports a coin cup 167 open at its upper end. The coin cup 167 constitutes the repository into which good coins are delivered after they have satisfactorily actuated the vending machine, in the manner hereinafter described.

Suitable means are preferably provided in the machine for preventing the machine from accepting coins when the supply of packages to be vended is exhausted. Various means of this type may be provided, but one type of means that has been found satisfactory comprises a pin or lever 169 (see Figures 2 and 3) pivoted intermediate its length on the right-hand side wall 15 and operating through a slot 170 therein. The pin 169 is spring pressed so that its lower end projects into the inside of the box-like container 17, while its other or upper end projects into the coin selecting device 163. When at least one package is present in the machine, the pin 169 is pressed against the side wall 19 by the package, thus removing the upper end of the pin 169 from its operative position in the coin selector 163. When no package is present in the vending machine, the spring presses the pin 169 so that its lower end extends into the boxlike structure 17, and its upper end extends across a passage in the coin selecting device 163 in such manner as to cause even good coins to be rejected thereby, and returned to the operator in the rejected coin chute 13. In this manner, when the operator presents a coin to an empty vending machine, the coin is not accepted, but is returned to him in the same manner as a slug.

Numeral 171 indicates a lever operated by camming engagement with the handle 15, and which in turn operates a wire 173 controlling a scavenging mechanism in the coin selector 163. Inasmuch as a particular construction of a coin selector 163, including said scavenger mechanism, forms no part of the present invention, further details of the construction and operation of the lever 171 and connecting wire 173 are not necessary herein.

The apparatus is loaded in the following manner, assuming that it is initially empty:

A supply of trays 53, equal in number to the capacity of the machine for packages to be dispensed, is provided. If the machine has been previously operated, this supply of trays will be found hanging in vertical position on the hook 59. If so, they are removed therefrom.

A first tray 53A is now placed in position with its notches 55 on the tracks 51, its rearward edge resting on the top flange 89 of the channel piece 87, and its front edge resting on the sloping flange 29 of the cross piece 27. Said tray is thus placed in horizontal position.

A first package P1 is now laid on the upper surface of the first tray 53A. The precise positioning of the package P1 on the tray 53A is immaterial, this being one of the features of advantage of the present invention.

A second tray 53B is now placed in position with its notches 55 engaging the track 51, said second tray 53B being supported entirely by resting on the top surface of the package P1. A second package P2 is now positioned atop the second tray 53B.

Successive additional trays 53 and packages P are similarly alternately stacked in the box-like structure 17 until said structure is substantially filled. It will clearly be seen that the packages P all support their own weight and the weight of the trays 53.

The box-like structure 17 as thus loaded is now positioned in the casing 1, and the front panel 3 locked in position thereon. The machine is now in condition for vending the packages P.

The dispensing action is brought about in the following manner: A purchaser, approaching the machine, places a coin C in the coin receiving slot 11. If the coin is a good one, it traverses the coin selector 163 and is deposited in the guide chute 157. If the coin is not a good one (i. e., it is a slug), or if the vending machine has been exhausted of packages, the slug or coin is returned to the operator through the reject chute 13.

However, a good coin C is delivered by the chute 157 and thereby falls into position between the quadrant plate 121 and the plate 109, resting on the upper edge of projecting area 115, and being prevented from rolling off said edge rearwardly by the pin 159 and forwardly by the projection 151.

The operator now presses the handle 15 downwardly. The pin 159 pushes the coin C forwardly along the upper edge 117 of projecting area 115, and the sloping front face of the coin C constitutes a cam which engages the projection 151 and causes it to ride upwardly along the edge of the coin, thereby lifting the lever 147 against the spring 155 (see Fig. 5).

As the handle 15 is pushed downwardly, and counterclockwise rotation of the quadrant plate 121 ensues, the channel piece 87 is likewise caused to rotate by the connecting piece 101.

The channel piece 87, however, rotates in a clockwise, rather than a counterclockwise manner. When rotation of this channel piece 87 has progressed to the point that upper flange 89 thereof is removed from under the rearward edge of the lowermost tray 53A, the rearward edge of said tray 53A, now being freed of support, commences to move downwardly, as guided by the track 51 and notches 55, pivoting on its front edge on the sloping flange 29 of cross piece 27. This action is indicated in Fig. 5. All of the other trays, and all of the packages, being freely supported on this first tray 53A, undergo similar movement.

However, while the upper flange 89 of channel piece 87 is brought to such a distance that it frees the rearward edge of tray 53A, the lower flange 91 is simultaneously brought into position such that it intercepts said rearward edge of the tray 53A in its movement (see Fig. 6). This happens about as the handle 15 reaches the downward limit of its movement. At the same time, the coin now has passed from under the projection 151 and lever 147, and over the front corner of upper edge 117 of the projecting area 115; the coin C consequently is free to fall downwardly, and does so fall, between the quadrant plate 121 and the plate 109, and ultimately into the coin cup 167.

As shown in Fig. 6, the lowermost tray 53A rests with its front edge still on the sloping flange 29 of cross piece 27, but with its rearward edge resting on the lower flange 91 of channel piece 87. The other trays, and all of the packages, are similarly positioned. It will be seen that the trays and packages are all at a relatively steep angle to the horizontal.

The operator now releases the handle 15, and, under the influence of tension spring 161, said handle 15 springs upwardly, and the quadrant plate 121 rotates clockwise to the other limit of its movement. In so doing, the following things happen:

First, as the channel piece 87 rotates, the lower flange 91 thereof is brought out from under the rear edge of tray 53A. This leaves the rear edge of said tray free to fall downwardly, which it proceeds to do. As the rear edge falls downwardly, it pulls the front edge of the tray off the sloping flange 29, thus releasing the front edge as well as the rear edge of the tray. For an instant, then, the tray is substantially free-falling, except for the guiding effect of tracks 51. However, as soon as the rear edge of the tray 53A comes to the ends of the tracks 51, as determined by points 63, the end 61 of hook 59 enters the hole 57 in said tray 53A, substantially to arrest movement of the rear edge of said tray. The tray 53A thereafter pivots on said hook 59, and the front edge of the tray 53A drops faster than the rear edge. Ultimately, the tray falls back against the back wall of the casing 1, hanging in vertical position as illustrated.

The package P1 follows the movement of the tray 53A until the package comes against the projecting parts of angle pieces 65 (see Fig. 3). These angle pieces 65 arrest and guide the movement of the package, and, together with the ears or projections 69, cause said package P1 to fall, under the influence of gravity, into the interior of dispensing box 9. The operator then pivots said dispensing box 9 forwardly, to its Fig. 3 dotted line position, and removes the purchased package at will.

As the first tray 53A and package P1 fall away 75

from the bottom of the stack, in the manner described, the second tray 53B moves downwardly under the weight of the packages and trays superimposed thereon. The first thing that happens 5 is that the rearward edge of the second tray 53B comes into contact with the spring-pressed strip 103, which acts as a brake to its movement. However, the strip 103 does not permanently impede the movement of said second tray 53B, because it springs aside under the weight of said tray and its superimposed load, to the dotted line position shown in Fig. 6, to permit the rear edge of said tray 53B to pass.

By the time the tray 53B gets past the strip 15 103, however, the channel piece 87 has returned in its rotation to the Fig. 4 position, and it accordingly intercepts the rear edge of said tray 53B, which comes to rest thereon. Meanwhile, the front edge of the tray 53B will have moved downwardly until it comes to rest against the sloping flange 29 of cross piece 27. The stack of trays thus resumes its original position, the only difference being that the lowermost tray 20 and package have been removed therefrom by the escapement mechanism.

Subsequent dispensing operations take place 25 in precisely the same manner as that described, until the last package in the machine has been dispensed.

It is impossible to cause the escapement mechanism to operate without presenting a good coin through the device, because without a coin in the position shown in Fig. 4, if an operator attempts to move the handle downwardly, he can do so only for an ineffective, limited movement, since the projection 151 of lever 147 will come up against shoulder 141 on the quadrant plate 121 and prevent further counterclockwise rotative movement of said quadrant plate. The proper 30 coin present in the device constitutes a cam arrangement that permits said projection 151 to ride up and pass over the shoulder 141 onto the angular section 137 of the quadrant lever 121.

The pawl 127 cooperating with the ratchet 125 35 on the quadrant plate 121 likewise provides that repeated dispensing cannot take place by oscillating the lever 15 up and down without discharging a single good coin placed therein. This is because, once the pawl 127 comes into engagement with the ratchet 125 on forward movement of said ratchet, it is impossible to move said ratchet rearwardly until its entire length has been traversed, and the pawl 127 freed from engagement with said ratchet. Once the entire 40 length of the ratchet has been traversed, the pawl will reverse its position to permit return movement of the quadrant plate 121, but by this time a single package has been dispensed and the coin presented to said package has been discharged into the coin cup 167.

In view of the above, it will be seen that the several objects of the invention are achieved and other advantageous results attained.

As many changes could be made in the above 45 constructions without departing from the scope of the invention, it is intended that all matter contained in the above description or shown in the accompanying drawings shall be interpreted in the accompanying drawings shall be interpreted as illustrative and not in a limiting sense.

I claim:

1. In a dispensing machine, a box-like structure for containing articles to be dispensed, vertical track means on one face of said structure, article-supporting trays engaging said track means to be guided in movement thereby, means

supporting the lowermost tray, the other trays being supported by the articles to be dispensed in alternating tray and article disposition in a stack resting on said lowermost tray, said lowermost tray supporting means comprising a relatively stationary rest for the front edge of the tray and a pivoted channel-shaped member for the rear edge of the tray, and means for oscillatably pivoting said channel-shaped member whereby said rear edge first rests on the top flange thereof, then falls from the top flange to the bottom flange thereof, and finally is released to fall from the bottom flange to deliver the article carried thereon.

2. In a dispensing machine, a box-like structure for containing articles to be dispensed, vertical track means on one face of said structure, article-supporting trays engaging said track means to be guided in movement thereby, means supporting the lowermost tray, the other trays being supported by the articles to be dispensed in alternating tray and article disposition in a stack resting on said lowermost tray, said lowermost tray supporting means comprising a relatively stationary rest for the front edge of the tray and a pivoted channel-shaped member for the rear edge of the tray, and means for oscillatably pivoting said channel-shaped member whereby said rear edge first rests on the top flange thereof, then falls from the top flange to the bottom flange thereof, and finally is released to fall from the bottom flange to deliver the article carried thereon, the rear edge of the said tray, in falling from said bottom flange of the channel-shaped member, causing the tray to slip rearwardly and disengage its front edge from the said rest therefor.

3. In a dispensing machine, a box-like structure for containing articles to be dispensed, vertical track means on one face of said structure, article-supporting trays engaging said track means to be guided in movement thereby, means supporting the lowermost tray, the other trays being supported by the articles to be dispensed in alternating tray and article disposition in a stack resting on said lowermost tray, said lowermost tray supporting means comprising a relatively stationary rest for the front edge of the tray and a pivoted channel-shaped member for the rear edge of the tray, and means for oscillatably pivoting said channel-shaped member whereby said rear edge first rests on the top flange thereof, then falls from the top flange to the bottom flange thereof, and finally is released to fall from the bottom flange to deliver the article carried thereon, the rear edge of the said tray, in falling from said bottom flange of the channel-shaped member, causing the tray to slip rearwardly and disengage its front edge from the said rest therefor, said track means terminating just beneath said channel-shaped member, and means beneath said track means receiving and collecting the trays successively discharged from the said channel-shaped member.

4. In a dispensing machine, a box-like structure for containing articles to be dispensed, vertical track means on one face of said structure, article-supporting trays engaging said track means to be guided in movement thereby, means supporting the lowermost tray, the other trays being supported by the articles to be dispensed in alternating tray and article disposition in a stack resting on said lowermost tray, said lower-

most tray supporting means comprising a relatively stationary rest for the front edge of the tray and a pivoted channel-shaped member for the rear edge of the tray, means for oscillatably pivoting said channel-shaped member whereby said rear edge first rests on the top flange thereof, then falls from the top flange to the bottom flange thereof, and finally is released to fall from the bottom flange to deliver the article carried thereon, and means in the box-like structure for receiving and guiding to a dispensing outlet the articles released from the trays as said trays successively fall from said channel-shaped member.

5. In a dispensing machine, a box-like structure for containing articles to be dispensed, vertical track means on one face of said structure, article-supporting trays engaging said track means to be guided in movement thereby, means supporting the lowermost tray, the other trays being supported by the articles to be dispensed in alternating tray and article disposition in a stack resting on said lowermost tray, said lowermost tray supporting means comprising a relatively stationary rest for the front edge of the tray and a pivoted channel-shaped member for the rear edge of the tray, means for oscillatably pivoting said channel-shaped member whereby said rear edge first rests on the top flange thereof, then falls from the top flange to the bottom flange thereof, and finally is released to fall from the bottom flange to deliver the article carried thereon, and brake means for resiliently breaking the fall of a next-higher tray into lowermost position, as a former lowermost tray is delivered from said channel-shaped member.

6. In a dispensing machine, a box-like structure for containing articles to be dispensed, vertical track means on one face of said structure, article-supporting trays engaging said track means to be guided in movement thereby, means supporting the lowermost tray, the other trays being supported by the articles to be dispensed in alternating tray and article disposition in a stack resting on said lowermost tray, said lowermost tray supporting means comprising a relatively stationary rest for the front edge of the tray and a pivoted channel-shaped member for the rear edge of the tray, means for oscillatably pivoting said channel-shaped member whereby said rear edge first rests on the top flange thereof, then falls from the top flange to the bottom flange thereof, and finally is released to fall from the bottom flange to deliver the article carried thereon, and brake means for resiliently breaking the fall of a next-higher tray into lowermost position, as a former lowermost tray is delivered from said channel-shaped member comprising a spring-pressed strip normally extending in the path of the rear edge of said next-higher tray but yieldably capable of being pushed aside to be passed by such rear edge.

7. In dispensing apparatus of the class described, escapement means comprising a bar having a channel-like cross section, the top flange making an obtuse angle with the rear web while the bottom flange is substantially perpendicular to the rear web, ears extending perpendicularly from the rear web at the ends of the bar and between the top and bottom flanges, and means pivotally supporting said bar at said ears.
